UNITED STATES PATENT OFFICE.

LOUIS A. DOURSON, OF CINCINNATI, OHIO, ASSIGNOR TO THE AMERICAN OIL PUMP & TANK CO., OF CINCINNATI, OHIO, A CORPORATION OF OHIO.

SELF-MEASURING OIL PUMP.

Application filed August 8, 1924. Serial No. 730,851.

To all whom it may concern:

Be it known that I, LOUIS A. DOURSON, a citizen of the United States, residing at Cincinnati, in the county of Hamilton and State of Ohio, have invented new and useful Improvements in Self-Measuring Oil Pumps, of which the following is a specification.

My invention relates to measuring pumps adapted to be used to handle a great variety 10 of liquids but which are particularly adapted to dispense lubricating oil. Garages and filling stations especially require such apparatus.

The principal object of the invention is 15 to provide a pump whose cylinder may be kept full of oil ready for immediate delivery, so constructed that the expansion of the oil in the cylinder will not cause the nozzle to drip, and at the same time will avoid bursting 20 the cylinders.

Another object of my invention is to provide a transparent measuring cylinder within 25 which the piston is reciprocated in full view and subject to the inspection of pursuers at all times.

Another object of my invention is to provide a simple, sturdy pump of pleasing appearance with a handle capable of being locked against rotation at any time.

30 My invention is illustrated in the accompanying drawings in which:

Figure 1 is a perspective of the pump mounted in position for use on an oil tank;

Fig. 2, an enlarged detail, is an axial section 35 through the combined top cylinder head and nozzle;

Fig. 3, a detail, is an enlarged perspective of the nozzle valve; and

Fig. 4 is an enlarged axial section thru 40 the pump heads, cylinder and piston, showing the rack and driving gear, with the piston at its extreme high position.

Referring now to the drawings:—1 is an oil tank with fill cap 2. A pump base 3 is 45 mounted upon said tank and raises the pump to a convenient height for use. A boss 4 on the side of the base is pierced to permit a locking rod 5 to be passed thru it and a hole 6 in the pump handle 7.

50 Surmounting the base is the lower cylinder head 8 which acts also as a casing for the gear 9 fixed to the shaft 10 which is rotated by the handle 7 thru stuffing-box 10a. Gear 9 is constantly in mesh with the

rack 11 and the rack and gear are held in 55 mesh by the flanged roller 12.

To the bottom of 8 is secured the usual supply pipe 13 which extends substantially to the bottom of the tank 1 and is provided with any convenient form of strainer 35. 60 A glass cylinder 14 is suitably mounted between the bottom cylinder head 8 and the top cylinder head 15, and tie rods 16 hold the parts securely in position.

To the top of the rack 11 is rigidly secured a piston consisting of a lower cage 17 having an axial valve rod 20, rigidly secured thereto and a valve seat 18 upon which seats a poppet valve 19. The poppet valve is bored axially at 22, a trifle large so as to 70 make a very easy fit on the valve rod 20 and permits oil in the top cylinder head and glass cylinder when expanded by heat to seep back downwardly thru the clearance space between the valve rod and poppet 75 valve sufficiently to ease the pressure but not enough to affect the measure substantially. The movement of the valve 19 on the valve rod 20 is a wiping action which maintains the minute clearance ring between 80 them. A top cage 21 holds the valve in position. The usual cup leather 23 and its sustaining spring 23a are provided. A screw 24 threaded axially thru the top cylinder head 15 extends downwardly so as to limit 85 the upward movement of the piston and when regulated is held in position by the lock nut 25 which is the bottom part of a cap which sustains an advertising sign 26.

A lug 38 on the bottom cylinder head 8, 90 limits the downward movement of the piston. On one side of the top cylinder head and integral with it is formed a nozzle casing 27 with oil passage 28, thru which the flow of oil from the interior 29 of the main body 95 of the top cylinder head is controlled by the poppet valve 30, having guide ribs 31, adapted to be guided by the hole 32. A vent hole 33 is provided from the top of the passage 28 to above the top of the valve 30. Into the outlet end of the passage 28 is fitted a nozzle tip 34, which so reduces the size of the opening that air will not go up into the nozzle and permit the oil to drip out. A cap 37 closes the opening in 100 the top of the nozzle casing.

A stand 36 is provided to support any receptacle used to catch the oil as it is

pumped out. It will be observed that there is no provision of any kind to catch drippings for there are none.

When the handle is turned the piston rises 5 and draws in oil thru the supply pipe and then at the same time discharges what oil is above the piston thru the nozzle to the container which is to supply oil to the customer. The poppet valve 30 rises from its seat during 10 the upstroke of the piston and on the downstroke is seated preventing air from reaching the top of the liquid in the pump, atmospheric pressure on the body of oil in the tank keeping the pump full of oil, and the poppet valve 19 in the piston opens on the return stroke of the piston allowing oil to flow up thru the cage 17 and past the valve 19 of the piston and fill the space in the cylinder above the piston. As soon as the piston ceases to move 15 downwardly the valve 19 closes enabling the pump to deliver the measured quantity of oil on the up-stroke of the piston. There is no check valve below the piston for the purpose of holding the liquid in the pump, the poppet valve 30 performing the function of the check valve usually placed below the piston. It will be evident that as long as the lower end of the pipe 13 is below the level of the liquid in the tank 1 and the poppet valve 30 is closed, no liquid can drain back from any part of the pump or suction pipe into the tank, other than that due to the expansion of the oil in 20 the pump and suction line.

It has been found that when the oil between the piston and the nozzle of a pump as usually constructed gets warmer and expands the excess volume created is discharged from the nozzle, causing dripping and consequently an unsightly appearance of the device. Furthermore, when the remaining oil gets cooler and contracts, the difference in volume causes air to enter the 25 pump through the nozzle and to fill the space previously occupied by the oil. On the next operation of the pump, this air causes the oil to sputter and spray over the pump and operator, and also causes the 30 pump to give short measure.

In my invention when expansion takes place, the excess oil between the piston and the nozzle does not go through the nozzle and cause dripping, but passes through the 35 small clearance space between the poppet valve 19 and the valve rod 20, then through the cage 17, the lower part of the cylinder 14, the interior of lower cylinder head 8 and supply pipe 13. When the oil cools and contracts, oil rises in the pipe 13 to cylinder head 8, lower part of cylinder 14, up thru 40 passage between 19 and 20, into the upper part of cylinder 14, keeping the cylinder full of oil at all times. The oil in the part 45 of pump below the piston can expand freely

into the reservoir or tank 1, since there is no check valve intervening. Contraction of oil in same part is compensated for by oil passing from the tank into and through the suction pipe.

I claim as my invention and desire to secure by Letters Patent of the United States:

1. A self measuring oil pump having in combination a pump cylinder, a discharge nozzle in fluid connection with said cylinder, a check valve in connection with said nozzle, reciprocating piston within said cylinder and means for allowing minute quantities of oil under pressure to seep back from the discharge side of said piston to the supply side. 75

2. A self measuring oil pump having in combination a pump cylinder, a discharge nozzle in fluid connection with the top of said cylinder, a check valve in connection with said nozzle, a reciprocating piston within said cylinder and means for allowing minute quantities of oil under pressure to seep back from the discharge side of said piston to the supply side. 80

3. A self measuring oil pump having in combination a pump cylinder, a top cylinder head, a discharge nozzle in fluid connection with said top cylinder head, a check valve in connection with said nozzle, a reciprocating piston within said cylinder and means for allowing minute quantities of oil under pressure to seep back from the upper to the under side of said piston. 95

4. A self measuring oil pump having in combination a pump cylinder, a top cylinder head in connection with a discharge nozzle, said nozzle, a valve within said nozzle, a reciprocating piston within said cylinder and means for allowing minute quantities of oil under pressure to seep back from the upper to the under side of said piston. 100

5. A self measuring oil pump having in combination a pump cylinder, a discharge nozzle in fluid connection with said cylinder, a check valve in connection with said nozzle, a nondrip tip for said discharge nozzle, reciprocating piston within said cylinder and means for allowing minute quantities of oil under pressure to seep back from the discharge side of said piston to the supply side. 110

6. A self measuring oil pump having in combination a pump cylinder, a discharge nozzle in fluid connection with the top of said cylinder, a check valve in connection with said nozzle, a nondrip tip for said discharge nozzle, a reciprocating piston within said cylinder and means for allowing minute quantities of oil under pressure to seep back from the discharge side of said piston to the supply side. 115

7. A self measuring oil pump having in 120

combination a pump cylinder, a top cylinder head, a discharge nozzle in fluid connection with said top cylinder head, a check valve in connection with said nozzle, a nondrip tip for said discharge nozzle, a reciprocating piston within said cylinder and means for allowing minute quantities of oil under pressure to seep back from the upper to the under side of said piston.

10. 8. A self measuring oil pump having in combination a pump cylinder, a top cylinder head in connection with a discharge nozzle, said nozzle, a valve within said nozzle, a nondrip tip for said discharge nozzle, a reciprocating piston within said cylinder and means for allowing minute quantities of oil under pressure to seep back from the upper to the under side of said piston.

15. 9. A self measuring oil pump having in combination a pump cylinder, a combined top cylinder head and discharge nozzle, a valve allowing oil to flow thru said nozzle but closing it against return therethru, a

reciprocating piston within said cylinder, an axially bored poppet valve in said piston 25 and a fixed valve stem for said poppet valve, the difference in diameter between said stem and the bore of said poppet valve being such as to allow minute quantities of oil under pressure to seep back from the upper 30 to the under side of said piston.

10. A self measuring oil pump having in combination a pump cylinder, a discharge nozzle in fluid connection with said cylinder, a reciprocating piston within said cylinder, 35 means for allowing minute quantities of oil under pressure to seep back from the discharge side of said piston to the supply side, a valve means between said cylinder and said discharge nozzle to prevent break in 40 vacuum when said piston is on the down-stroke.

In testimony whereof I have hereunto set my hand.

LOUIS A. DOURSON.
